(57) **CLAIM**

I claim the ornamental design for a packaging for a toy, as shown and described.

DESCRIPTION

FIG. 1 is a front perspective view of a packaging for a toy, showing my new design.

FIG. 2 is a front view of the packaging for a toy of FIG. 1.

FIG. 3 is a rear view of the packaging for a toy of FIG. 1.

FIG. 4 is a left side view of the packaging for a toy of FIG. 1.

FIG. 5 is a right side view of the packaging for a toy of FIG. 1.

FIG. 6 is a top view of the packaging for a toy of FIG. 1; and, FIG. 7 is a bottom view of a packaging for a toy of FIG. 1. The broken lines shown in the drawings are for illustrative purposes only and form no part of the claimed design.

The stippling and shading lines shown in the drawings represent the approximate three-dimensional contour of the design, and are not intended to indicate surface decoration.
